[57] CLAIM

The ornamental design for a beverage carrying tray, as shown and described.

DESCRIPTION

FIG. 1 is a top perspective view of a beverage carrying tray showing our new design;

FIG. 2 is a bottom perspective view thereof;

FIG. 3 is a side elevational view thereof, the pivotal handles being in a typical carrying position;

FIG. 4 is an end elevational view thereof;

FIG. 5 is a top plan view thereof;

FIG. 6 is a bottom plan view thereof; and

FIG. 7 is a side elevational view thereof, the pivotal handles being arranged in an overlapping folded position between beverage containers which are shown in broken lines for illustrative purposes only.
